COCKING MECHANISM FOR GUNS.

No. 865,810.

Specification of Letters Patent.

Patented Sept. 3, 1907.

Application filed April 2, 1898. Serial No. 676,180.

To all whom it may concern:

Be it known that I, CHARLES F. LEFEVER, of Syracuse, in the county of Onondaga, in the State of New York, have invented new and useful Improvements in 5 Cocking Mechanism for Guns, of which the following, taken in connection with the accompanying drawing, is a full, clear, and exact description.

My invention relates to cocking mechanism for breech-loading guns, and the object thereof is to provide such mechanism which is particularly simple in 10 construction, economical in manufacture, and efficient and durable in use.

To this end, the invention comprises the parts, and the combinations and arrangements of component 15 parts to be hereinafter described and particularly pointed out in the claims.

The invention is susceptible of various embodiments, but for the purpose of clearly disclosing the same, I have illustrated in the accompanying drawings, and 20 shall hereinafter describe in connection therewith, what is now conceived to be a preferable embodiment.

In these drawings—Figures 1 and 2 are elevations, partly in section, of a portion of a gun equipped with my cocking mechanism, the barrels being shown in 25 their normal positions in Fig. 1, and as broken or dropped in Fig. 2. Fig. 3 is an elevation, partly in section, of the portion of a gun seen in the preceding figures, the fore-end being removed, and the barrels being shown in the position assumed when about to 30 be disconnected from the breech. Fig. 4 is an inverted plan view of the rear ends of the gun-barrels seen in the preceding figures. Fig. 5 is an isometric view of the hammers and cocking lever detached from the other mechanism of the gun.

35 My cocking mechanism includes generally a cocking lever A, associated with the hammer or hammers a of the gun, engaging means B associated with the barrel or barrels b of the gun, and engaging means associated with, or constituting a part of, the cocking lever 40 coacting with the means B. The cocking lever A is usually connected to the hammers a with a lost motion, being here illustrated as having its rear end fixed to the hammer-pivotal pin a', which is provided with feathers or keys a², movable in key-ways or grooves a³ 45 in the journal-openings of said hammers.

50 My invention contemplates the provision of means associated with the hammer or hammers and co-operating with the means B for cocking the hammers during the dropping of the barrels and for arresting the drop thereof, which means is separable from the means B while the hammers are in their uncocked or cocked position, and when the barrels are in a substantially closed position, so that by a slight endwise movement of the latter they may be detached from the breech.

55 A further object contemplated is a construction in

which an increasing leverage is obtained for cocking the hammers as the barrels attain the limit of their breaking or dropping movement for the purpose of compensating for the increasing tension of the main springs of the hammers.

60

The engaging means associated with the hammers, contemplated by the invention preferably includes an elongated bearing surface normally located above and substantially in front of the means B and unobstructed at one end, and a second surface or abutment at the opposite end of the first surface and disposed at an angle thereto for the purpose of arresting the travel or slidable movement of the element B along said elongated surface, as will hereinafter appear. The element B preferably occupies a position in close proximity to the unobstructed end of the first surface when the barrels are in substantially closed position, so that by a slight endwise movement of the latter the element B may be entirely disengaged from said surface. Said element B is here shown as a shoulder projecting 70 from the inner faces of a groove b' which is formed in the barrel-lug b² and receives the free end of the cocking lever.

In the particular embodiment of the invention illustrated in the drawings, the elongated surface slidably 80 engaged by the element B to effect the cocking of the hammers is provided by the underside a⁴ of the bill of a hook formed integral with the cocking lever A, and the second surface or abutment is provided by the inner side of the bail a⁴ of the hook or the portion joining the bill to the main body, said hook forming a rigid extension of the cocking lever. As will be noted, the space between the body and the bill constitutes a slot a⁶ in which the element B is guided; this slot having its front end closed to arrest the movement of 90 the element B, and its rear end unobstructed and opening through the upper face of the lever A to permit the element B to pass entirely out of said slot. As will be appreciated, in the breaking or dropping of the barrels, the element B travels from its normal resting point, toward the closed end of the slot, thus gradually increasing the leverage of the cocking lever A as the tension of the hammer-springs is increased, and when the element B abuts against the second surface the further dropping of the barrels is arrested. It will 95 be understood, however, that before the element B comes into engagement with the second surface or abutment, the hammers a are engaged by suitable sears a⁷, which act in the well known manner for holding the hammers in their cocked positions. When the barrels are being closed, the element B travels along the surface a⁵, and as said barrels reach the limit of their closing movement, the element B substantially passes from beneath the surface a⁵ which, even when the hammers 100 are uncocked, is arranged out of the path in which 105

the further dropping of the barrels is arrested. It will be understood, however, that before the element B comes into engagement with the second surface or abutment, the hammers a are engaged by suitable sears a⁷, which act in the well known manner for holding the hammers in their cocked positions. When the barrels are being closed, the element B travels along the surface a⁵, and as said barrels reach the limit of their closing movement, the element B substantially passes from beneath the surface a⁵ which, even when the hammers are uncocked, is arranged out of the path in which 110

the element B is movable with the barrels during the detachment and replacement of the barrels. The barrels *b*, as here shown, are so connected to the breech of the gun that when the fore-end *b*³ is removed and the 5 barrels slightly broken, as illustrated in Fig. 3, they may have a limited endwise movement rearwardly, in order that the element B may be entirely disengaged from the elongated surface, or moved entirely out of the slot *a*⁶, thus freeing the barrels so as to permit 10 upward movement of the rear ends of the same independently of the cocking lever, and the subsequent detachment of the barrels from the breech.

In the illustrated embodiment of the invention, a double-barreled gun is shown, and the invention has 15 been described particularly in connection therewith, but it is obvious that my mechanism is equally applicable in a single-barreled gun.

The construction and operation of my cocking mechanism will be readily understood upon reference to the 20 foregoing description and accompanying drawings, and it will be apparent that considerable change may be made in the details of construction and arrangement of the component parts, without departing from the spirit of the invention.

25 Having thus described my invention, what I claim as new, and desire to secure by Letters Patent, is:—

1. In a breech-loading gun, the combination with a hammer and a barrel, of engaging means associated with the barrel, an elongated surface associated with the hammer 30 slidably engaged by said means during the dropping of the barrel for cocking the hammer, and a second surface engaged by said means to arrest dropping of the barrel, said means substantially passing from beneath the end of the first surface as the barrel reaches a substantially 35 closed position, substantially as and for the purpose specified.

2. In a breech-loading gun, the combination with a barrel, a hammer and a cocking lever, of an elongated bearing surface rigid with the lever, substantially unobstructed 40 at one end and having an abutment at its opposite end, and engaging means associated with the barrel occupying a position adjacent the unobstructed end of the surface when the barrel is in closed position, and traveling along said surface and coacting therewith to shift the cocking 45 lever as the barrel is dropped, and engaging said abutment at the limit of its travel to arrest the dropping of the barrel, substantially as and for the purpose described.

3. In a breech-loading gun, the combination with a barrel, a hammer and a cocking lever, of parts rigid with the 50 barrel and cocking lever and coacting with each other for shifting the cocking lever during the dropping of the barrel and for arresting the movement of the barrel, the part associated with the cocking lever having its surface for coacting with the part associated with the barrel to shift 55 the cocking lever during the dropping of the barrel, arranged when the hammer is uncocked, out of the path in which the part associated with the barrel moves during the detachment and replacement of the barrel, substantially as and for the purpose described.

60 4. In a breech-loading gun, the combination with a barrel, a hammer and a cocking lever, of parts rigid with the barrel and cocking lever and slidably coacting with each other for shifting the cocking lever during the dropping of the barrel said parts coacting with each other for arresting 65 the movement of the barrel, the part associated with the cocking lever having its surface for coacting with the part associated with the barrel to shift the cocking lever during the dropping of the barrel, normally arranged substantially in front of the path in which the part associated 70 with the barrel moves during the removal and replacement of the barrel, substantially as and for the purpose set forth.

5. In a breech-loading gun, the combination with a barrel, a hammer and a cocking lever, of an element rigid

with the barrel, engaging surfaces on the lever at gradually increasing distances from the pivot thereof said surfaces being rigid with the lever and coacting with said element for shifting the cocking lever as the barrel is dropped, and a surface disposed at an angle to the other surfaces for arresting the dropping of the barrel, substantially as and for the purpose specified. 75

6. In a breech-loading gun, the combination with a barrel, a hammer and a cocking lever, of an element rigid with the barrel, engaging surfaces on the lever at gradually increasing distances from the pivot thereof said surfaces being rigid with the lever and coacting with said element for shifting the cocking lever as the barrel is dropped, and a surface disposed at an angle to the other surfaces for arresting the dropping of the barrel, said first-mentioned surfaces, when the hammer is uncocked, being arranged out of the path in which said element is movable with the barrel during the detachment and replacement of the barrel, substantially as and for the purpose described. 80

7. In a breech-loading gun, the combination with a barrel, a hammer and a cocking lever, of an element rigid with the barrel, engaging surfaces on the lever at gradually increasing distances from the pivot thereof said surfaces being rigid with the lever and coacting with said element for shifting the cocking lever as the barrel is dropped, and a surface disposed at an angle to the other surfaces for arresting the dropping of the barrel, said first-mentioned surfaces being normally arranged substantially in front of the path in which said element is movable with the barrel during the detachment and replacement of the barrel, substantially as and for the purpose 85 specified. 90

75

8. In a breech-loading gun, the combination of a hammer, a barrel provided with engaging means, and a cocking lever for the hammer, said cocking lever having a surface rigid therewith arranged above the engaging means provided on the barrel and coöperating with such means for causing the cocking lever to cock the hammer, and said cocking lever also having a surface arranged in front of said engaging means and coöperating therewith for limiting the dropping movement of the barrel, substantially as and for the purpose specified. 100

9. In a breech-loading gun, the combination of a hammer, a barrel provided with engaging means, and a cocking lever for the hammer, said cocking lever being provided at its front end with an extension rigid therewith having a surface arranged above the engaging means provided on the barrel and slidably coöperating with such means for causing the cocking lever to cock the hammer, said extension also having a surface arranged in front of said engaging means and coöperating therewith for limiting the 110 dropping movement of the barrel, substantially as and for the purpose specified. 115

10. In a breech-loading gun, the combination of a hammer, a barrel provided with engaging means fixed thereto, and a cocking lever for the hammer, said cocking lever being provided with a part rigid therewith having a surface arranged above the engaging means fixed to the barrel and engaging the upper face of such means for causing the cocking lever to cock the hammer, said part also having a surface arranged in front of said engaging means and engaging the front face of such means for limiting the dropping movement of the barrel, substantially as and for the purpose set forth. 120

11. In a breech-loading gun, the combination of a hammer, a barrel provided with engaging means, and a cocking lever, said cocking lever having a part thereof rigid therewith and arranged below the engaging means provided on the barrel and also having a part rigid with the former part and projecting therefrom in front of such engaging means and having a surface above such engaging 125 means and slidably coöperating therewith for causing the cocking lever to cock the hammer, substantially as and for the purpose specified. 130

140

12. In a breech-loading gun, the combination with a barrel and a hammer, of a cocking lever having a rigid part formed with a slot therein provided with a closed end and an open end, the latter end of the slot opening through the upper face of the cocking lever, and fixed means carried by the barrel and slidably coacting with the wall of the 150

- slot to effect the cocking of the hammer, said means traveling toward the closed end of the slot in the cocking action, substantially as and for the purpose described.
13. In a breech-loading gun, the combination with a barrel, and a hammer, of a cocking lever having a part rigid therewith formed with a slot therein provided with a closed end and an open end, and fixed means carried by the barrel and slidably coacting with the wall of the slot to effect the cocking of the hammer, said means traveling toward the closed end of the slot in the cocking action, and passing substantially through the open end of the slot as the barrel reaches its closed position, substantially as and for the purpose set forth.
14. The combination of a hammer, a cocking lever connected to the hammer and having a rigid engaging surface, and a barrel provided with a fixed shoulder for engaging said rigid surface to actuate the cocking lever, said surface, when the hammer is uncocked, being arranged out of the path in which said shoulder is movable with the barrel during the detachment and replacement of the barrel, substantially as and for the purpose specified.
15. The combination of a hammer, a cocking lever having a rigid engaging surface, means connecting the cocking lever to the hammer for cocking the hammer and permitting said cocking lever to move independently of the hammer when cocked, and a barrel provided with a fixed shoulder for engaging said rigid engaging surface to actuate the cocking lever, said surface, when the hammer is uncocked, being arranged out of the path in which said shoulder is movable with the barrel during the detachment and replacement of the barrel, substantially as and for the purpose described.
16. The combination of a hammer, a cocking lever connected to the hammer and provided with a lengthwise rigid shoulder, and a barrel provided with means for slidably engaging said lengthwise shoulder and actuating the cocking lever, said shoulder being normally arranged substantially in front of the path in which said means is movable with the barrel during the detachment and replacement of the barrel, substantially as and for the purpose set forth.
17. The combination of a hammer, a cocking lever connected to the hammer and provided at its free end with a lengthwise shoulder having its front extremity rigid with the remaining portion of the cocking lever and its lower face and rear extremity separated from the contiguous portion of said lever, and a barrel provided with means for slidably engaging said lengthwise shoulder and actuating the cocking lever, substantially as and for the purpose specified.
- 50 18. The combination of a hammer, a cocking lever pro-

vided at its free end with a lengthwise shoulder having its front extremity rigid with the remaining portion of the cocking lever and its lower face and rear extremity separated from the contiguous portion of said lever, means for connecting the cocking lever to the hammer for cocking the hammer and permitting said cocking lever to move independently of the hammer when cocked, and a barrel provided with means for slidably engaging said lengthwise shoulder and actuating the cocking lever, substantially as and for the purpose described.

19. The combination of a hammer, a cocking lever connected to the hammer and provided at its free end with a lengthwise shoulder having its front extremity rigid with the remaining portion of the cocking lever and its lower face and rear extremity separated from the contiguous portion of said lever, and a barrel provided with a fixed shoulder for slidably engaging the former shoulder and actuating the cocking lever, said barrel being movable endwise for disengaging its shoulder from the cocking lever, substantially as and for the purpose set forth.

20. The combination of a hammer, a cocking lever connected to the hammer and having a rigid part provided with a forwardly-extending slot open at its rear end, and a barrel provided with a shoulder movable in said slot, substantially as and for the purpose specified.

21. The combination of a hammer, a cocking lever connected to the hammer and having a rigid part provided with a slot extending downwardly and forwardly from its upper face, and a barrel provided with a fixed shoulder movable in said slot, substantially as and for the purpose described.

22. The combination of a hammer, a cocking lever connected to the hammer and having a rigid part provided with a forwardly-extending slot open at its rear end, and a barrel having a lug provided with a groove for receiving the cocking lever and a shoulder projecting from one of the inner faces of the groove in said lug for entering the slot of the cocking lever, said barrel being movable endwise for removing the shoulder from the open rear end of the slot in the cocking lever, substantially as and for the purpose specified.

In testimony whereof I have hereunto signed my name in the presence of two attesting witnesses, at Syracuse, in the county of Onondaga, in the State of New York, this 9th day of March, 1898.

CHARLES F. LEFEVER.
